UNITED STATES PATENT OFFICE.

SAMUEL W. JACKSON, OF CHICAGO, ILLINOIS.

HEATING-DRUM FOR LAMP-STOVES.

SPECIFICATION forming part of Letters Patent No. 269,423, dated December 19, 1882.

Application filed November 14, 1881. Renewed October 18, 1882. (No model.)

To all whom it may concern:

Be it known that I, SAMUEL W. JACKSON, of Chicago, in the county of Cook and State of Illinois, have invented certain new and useful Improvements in Heating-Drums for Lamp-Stoves; and I do hereby declare that the following is a full, clear, and exact description thereof, reference being had to the accompanying drawings, and to the letters of reference marked thereon, which form a part of this specification.

The object of this invention is to produce a heating-drum for lamp or oil stoves which will be more effective in heating the air in the room in which the stove is located by inducing a current of air through the drum, wherein the same is mingled with the products of combustion from the stove; and to this end it consists in a drum having the features of construction hereinafter described and claimed.

In the drawings, Figure 1 is a central vertical section of a drum embodying my invention and the upper part of an oil or lamp stove on which it is used. Fig. 2 is a horizontal section in the line $z z$ of Fig. 1, looking upward. Fig. 3 is a horizontal section in the line $x x$, Fig. 1, looking downward. Fig. 4 is a horizontal section in the line $y y$, looking downward.

30 A is a sheet-metal cylindric drum, somewhat larger in diameter than the stove B, to which it is to be applied. The lower end of the drum is open, and provided with the arms a , projecting obliquely inward and upward, and having 35 hooks a' at their upper and free ends, which set over the stove-top, and thereby sustain the drum in position for use, as indicated in Fig. 1. By reason of the greater diameter of the drum an annular space, b , is afforded between the drum 40 and the stove.

C is a deflecting-plate, preferably of conical form, as shown, having a central opening, c , and secured by its margin to the wall of the drum A a short distance above the top of the 45 stove. A little above the conical deflecting-flange C is located a horizontal deflecting-disk, D, arranged concentric with the drum to give the annular passage d around it, and supported by the brackets d' or otherwise.

50 E is a horizontal deflecting-flange projecting inwardly from the wall of the drum A, and secured between the deflecting-disk D and the drum-top A', provided with any desired number of apertures, a^2 , distributed over its area. In

operation the heated products of combustion 55 rise into the lower portion of the drum A, and, following the course indicated by the arrows through the several passages c , d , and e , escape through the apertures a^2 in the top A'. A current of air is thereby induced through 60 the space b into the drum A, where it unites with the current of combustion products, and in rising through the circuitous passage within the drum, as indicated, the two become thoroughly intermingled and of common temperature. 65 By the arrangement of the conical flange C and disk D these parts are directly heated by radiation from the flames of the stove, as well as by contact with the hot products of combustion, and thereby materially 70 increase the temperature of the combined products and air emerging through the perforated top plate, A'.

Obviously the drum may be supported in position with reference to the stove by other 75 forms of arms than those shown at a .

I claim as my invention—

1. In combination with a lamp-stove, a heating-drum having at its base, when applied to the stove, a space, b , for the admission of air, and provided with the deflecting-flange C and disk D, arranged to intercept heat radiated from the flame and to give off the same to the passing current of induced air, substantially as described.

2. In combination with a lamp-stove, B, a drum, A, provided with suitable means for supporting the same in position, and having an open space about its base for the induction of outer air, and having the flange C, against which the admitted air impinges, the central disk D, the flange E, and the apertured top A', arranged and operating as and for the purposes specified.

3. In combination with the stove B, the open-bottomed drum A, larger than the stove, and provided with the inwardly-directed hooks a , arranged to engage the stove-top, and thus support the drum concentric with the stove, substantially as shown and described.

In testimony that I claim the foregoing as my invention I affix my signature in presence of two witnesses.

his
SAMUEL W. X JACKSON.
mark.
